SOIL ENGINEER'S SURVEY TOOL

John Lowe III, 26 Grandview Blvd., Yonkers, N.Y.

Filed Dec. 16, 1964, Ser. No. 83,053

Term of patent 14 years

(Cl. D54—13)

FIGURE 1 is a front elevational view of a soil engineer's survey tool showing my new design.

FIGURE 2 is a side elevational view of the tool as viewed at the left of FIGURE 1.

FIGURE 3 is a fragmentary view of the lower end thereof, taken on an enlarged scale.

The side opposite that shown in FIG. 1 is a substantial mirror image thereof.

I claim:

The ornamental design for a soil engineer's survey tool, as shown and described.
